William Richards

UNITED STATES PATENT OFFICE.

FRIEDRICH O. VONTOBEL, (NOW BY JUDICIAL CHANGE OF NAME MARCELLE JOHN HARDING,) OF NEW YORK, N. Y.

COLLAR-BUTTON.

1,314,837.

Specification of Letters Patent.

Patented Sept. 2, 1919.

Application filed December 21, 1918. Serial No. 267,764.

To all whom it may concern:

Be it known that I, FRIEDRICH OTTO VONTOBEL, a citizen of Switzerland, residing at New York, in the county and State of New York, have invented certain new and useful Improvements in Collar-Buttons, of which the following is a specification.

This invention relates to collar buttons, and has for its object to produce such a device that can be cheaply and easily made; that can be easily secured in the collar band of the shirt, and to which the collar may be readily applied.

Other objects are to provide a collar button that will have means whereby the collar may be retained securely in place without danger of displacement; that will have means whereby the collar will be held in place without liability to accidentally become detached from the button, but which will be retained thereon until purposely removed; to form the button so that it will present no obstacle to the easy movement of a neck-tie in the collar when tying or otherwise; and finally, to so construct the button that it will rest easily against the person of the user when in use, and without tending to displace the collar or any portion thereof from its proper position.

These and other objects of my invention are set forth in the following specification and shown in the accompanying drawing which forms a part thereof, the particular features of novelty which constitute my invention being pointed out in the claims at the end thereof.

In the drawings:—

Figure 1, is a perspective view of a top of a shirt and collar, showing my invention as applied thereto;

Fig. 2 is a fragmental sectional view taken on the line 2—2 of Fig. 1;

Fig. 3 is a fragmental perspective view illustrating the method of inserting my collar button in the button hole of a collar; and

Fig. 4 is a perspective view of the collar button separately.

Referring to the drawings, 10 indicates the upper portion of a shirt, and 11 a collar band thereof; 12 represents a collar. All the above parts may be of a conventional or any desired form or shape. The

collar band is provided with the usual button hole 13 through which the neck of the 55 collar button passes.

My improved collar button consists of a band 14, which is shaped to fit the neck of a user, of a constricted neck piece 15, and with a head 16, an upwardly projecting transverse rib 17 being positioned at the end of the neck 15 and projecting in an upward position from the neck 16 so that the top surface of the neck 15 presents a seat in which the upper portion of the collar band 65 11, and the end tabs 18—18' rest and are securely held in place therein by the rib 17, so that they cannot be accidentally displaced therefrom. The head 16 is provided with lateral wings 19 and 20, which extend outwardly from the head a sufficient distance so that the wings from end to end are wider than the button holes 21 of the collar with which they are to engage, so that the collar when once buttoned and in place upon the 75 neck 15, is held thereon against accidental displacement and until purposely removed therefrom.

In inserting the head 16 through a button hole 21, a collar as shown in Fig. 3 may 80 be inclined somewhat with respect to the head 16, so that one wing and the point 22 of a head may first be inserted in the button hole, this being permitted as the distance between said point and the end of either 85 wing is less than the length of the button hole. The collar is then turned so that the other wing may easily pass into the button hole, and when the collar is in place upon the neck 15, the two wings extending beyond 90 the ends of the button hole will hold the collar in place upon the neck 15 as above described.

My improved collar button is so formed that the band and head thereof extend in 95 opposite directions in planes parallel with each other, the band and head being separated from each other only a sufficient distance to properly accommodate the thickness of the shirt collar band, and of the collar, the band of the collar button resting upon the neck, and the latter holds the parts in such a position that no pressure of the collar or necktie used therewith will materially change the position of the collar 100 button, or cause undue or annoying pres-

sure upon the neck of the user, or cause the collar button to assume an undesirable position.

What I claim as new and desire to secure 5 by Letters Patent, is:

1. A collar button comprising a band suitable to the neck of the wearer, a neck projecting rectangularly therefrom and provided with a transverse rib, and a head depending from the end of said neck having 10 on opposite sides wings projecting laterally beyond the said neck.

2. A collar button comprising a base, a neck projecting therefrom rectangularly and provided with a transverse rib, and a head 15 depending from the end of said neck having lateral wings of a width from end to end substantially double the width of the said neck.

In testimony whereof, I have signed my 20 name to this specification, this 10th day of December, 1918.

FRIEDRICH O. VONTOBEL.
